KITE STRING REEL

Thomas F. Nieman, Denver, Colo., assignor to The Saturn Corporation, Denver, Colo., a corporation of Colorado

Filed July 11, 1966, Ser. No. 3,032

Term of patent 14 years

(Cl. D41—1)

FIG. 1

FIG. 4

FIG. 2

FIG. 3

FIG. 1 is a perspective view of a kite string reel embodying my new design;

FIG. 2 is a bottom plan view;

FIG. 3 is an end elevational view; and

FIG. 4 is a cross-sectional view thereof taken along section line 4—4 of FIG. 2.

I claim:

The ornamental design for a kite string reel, substantially as shown and described.
